RECLINING ARTICLE OF FURNITURE

Anton Lorenz, Buffalo, N. Y.

Application October 26, 1945, Serial No. 624,862

6 Claims. (Cl. 155—106)

1

My invention relates to an article of furniture, and more particularly to a reclining article of furniture, wherein the back-rest and seat form movable members of a polygonal link-system swingably mounted on a support of connected side frames, and wherein the movements of the members of said polygonal link-system are positively controlled by a guiding link pivoted to the support and operatively connected with a member of the polygonal link-system.

An object of my invention is to provide a convenient controlling mechanism for a leg-rest swingably mounted on the seat of a reclining article of furniture of above described type, by means of which the angle between the leg-rest and the seat is automatically altered when the movable members of the reclining article of furniture including the back-rest and the seat are brought from a certain position, such as the sitting position, into another position, such as a reclined position, or vice versa.

Another object of my invention is to improve on reclining articles of furniture of above described type as now ordinarily made.

The above mentioned objects and advantages as well as other objects and advantages will be more fully disclosed in the following specification, reference being had to the accompanying drawings forming part of this specification, wherein:

Fig. 1 is a side elevational view of an adjustable reclining chair according to the invention, a portion of the support being broken away for a better illustration of the mechanism.

Fig. 2 is a perspective view of the support of the chair shown in Fig. 1.

Fig. 3 is a sectional view taken on line 2—2 of Fig. 1, illustrating the locking device of the chair.

Fig. 4 is a side elevational view of a different embodiment of an adjustable reclining chair according to the invention, a portion of the support being broken away.

Fig. 5 is a side elevational view of another embodiment of an adjustable reclining chair according to the invention, a portion of a side frame being broken away.

Fig. 6 is a side elevational view of an arm-chair according to the invention which may be converted into a bed or the like, a portion of a side frame being broken away.

Fig. 7 is a perspective view of the frame structure of a different embodiment of an arm-chair according to the invention, some parts being broken away for a better illustration of the mechanism.

Fig. 8 is a somewhat diagrammatical perspec-

2

tive view of a different embodiment of a mechanism according to the invention.

Fig. 9 is a side elevational view, partly in section, of a different pivotal connection between the seat and the leg-rest of a chair according to the invention.

Fig. 10 is a side elevational view of another embodiment of an adjustable reclining chair according to the invention, a portion of a side frame being broken away.

Fig. 11 is a side elevational view of a further embodiment of a chair according to the invention, a portion of the side frame being broken away.

Fig. 12 is a side elevational view of still another embodiment of a chair according to the invention, a portion of a side frame being broken away.

Fig. 13 is a sectional view taken on line 13—13 of Fig. 12, and

Fig. 14 is a fragmentary view of a different embodiment of a controlling mechanism according to the invention.

Referring now to Figs. 1 and 2, 20 generally indicates a support in the shape of a casing, the side walls or side frames 22, 24 of which are connected with each other by the rear wall 26 and front wall 28. The arm-rests 30 are integral with the body of the support 20.

The rear end of the seat 32 is pivoted to the back-rest 34 at 36. The back-rest 34 has an extension 38 projecting downwardly beyond said pivotal connection 36 between the back-rest and the seat. One end of a connecting link 40 arranged substantially in the center of the chair and hereinafter called the lower connecting link is pivoted at 42 to said extension 38 of the back-rest, the other end of said lower connecting link 40 is pivoted to one end of a second connecting link 44 hereinafter called the front connecting link at 46.

The other end of said front connecting link 44 is pivoted to the seat 32 at 48. Thus, the pivotally interconnected extension 38 of the back-rest, the link-chain composed of the two connecting links 40, 44, and the seat 32 form the movable members of a polygonal link-system in the shape of a quadrilateral link-system. Said quadrilateral link-system is swingably mounted on the support 20 at the pivotal connection 36 between the back-rest and the seat for movement about a single axis; the pivot 36 connecting the seat 32 with the back-rest 34 is inserted into a bore 50 arranged on the support. The movements of the movable members of said quadrilateral link-system are controlled by a guiding link 52, the upper end of which is swingably mounted on a

55

transverse rod 54 carried by the support, and the lower end of which is pivoted to the link-chain or pair of connecting links at the pivotal connection 46 between the connecting links 40 and 44.

A leg-rest 56 is pivoted to the front portion of the seat 32 at 58. According to the invention, the movements of said leg-rest 56 are controlled by a controlling link 60, one end of which is pivoted to the leg-rest at 62, and the other end of which is pivoted to an intermediate point of the guiding link 52 at 64. Said controlling link 60 passes through a recess 66 of the front wall 28 of the support.

The sitting position of the movable members of the chair shown in full lines is limited by the upper edge 68 of the support, on which the seat comes to a rest.

When the occupant of the chair leans the weight of his body against the back-rest, he may readily swing the movable members of the chair into a reclined position, for example into the extreme reclined position shown in dash and dot lines in Fig. 1. As mentioned above, during such a movement the guiding link 52 controls the movements of the members 32, 38, 40, 44 of the quadrilateral link-system and the movements of the leg-rest 56 through the medium of the controlling link 60.

The extreme reclined position is limited by an abutment of the back-rest 34 against a stop 70, forming a part of the support 20.

The movable members of the chair may be held in any desired position by means of a locking device generally indicated by 12. As best shown in Figs. 1 and 3, said locking device comprises a rod 74 pivoted to the seat 32 at 76. A bolt 78 having a head 80 and a threaded end 82 is inserted into bores 84 of a clamping sleeve 86 engaged with said rod 74.

The bolt 78 has a projection 88, which is in engagement with a recess of the clamping sleeve 86 so as to prevent the bolt 78 from rotation. A tubular member 90 inserted into a hole 92 of the side wall 22 of the support 20 is arranged between the clamping sleeve 86 and a locking knob 94 screwed on the threaded end 82 of the bolt 78. When said locking knob 94 is loosened, the rod 74 may freely slide in the clamping sleeve 86, so that the movable members of the chair may be readily moved from one position into another one. If the locking knob 94 is tightened, the tubular member 90 and the head 80 of the bolt 78 press against the clamping sleeve 86, whereby the latter is tightly pressed against the rod 74, so that the movable members of the chair are held in the adjusted position.

In the embodiment of an adjustable reclining chair shown in Fig. 4, the quadrilateral link-system is formed by the extension 138 of the back-rest 134, the lower connecting link 140, the front connecting link 144 and the seat 132. Said quadrilateral link-system is pivoted to the support 120 at 136 and the movements of its members are again controlled by a guiding link 152. The upper end of said guiding link is swingably mounted on a transverse rod 154 carried by the support, and the lower end of said guiding link is pivoted to the pivotal connection 146 between the lower connecting link 140 and front connecting link 144. Said guiding link 152 also controls the movements of the leg-rest 156 pivoted to the seat at 158 through the medium of the controlling link 160, one end of which is pivoted to the leg-rest at 162. In contrast to Fig. 1, however, the other end of the controlling link 160 shown

in Fig. 4 is pivoted to the pivotal connection 146 between the guiding link 152 and a connecting link of the quadrilateral link-system.

The sitting position of the movable members of the chair shown in Fig. 4 is limited by the upper edge 168 of the front wall 128 of the support, and the extreme reclined position is limited by the edge 170 of a recess in the rear wall 126 of the support.

The operation of the chair shown in Fig. 4 substantially corresponds to the operation of the chair shown in Fig. 1, the movements of the members of the quadrilateral link-system and of the leg-rest being controlled by the guiding link 152.

In the embodiment of an adjustable reclining chair shown in Fig. 5, 220 generally indicates a support comprising the side frames 222 and 224 connected with each other by transverse rods 226 and 228. If desired, the support 220 may be made of an integral piece of tubular material.

The seat 232 is pivoted to the back-rest 234 at 236, and the back-rest has an extension 238 projecting downwardly from said pivot 236. On each side of the chair, one end of the lower connecting link 240 is pivoted to the extension 238 of the back-rest at 242. The other end of each lower connecting link 240 is pivoted at 245 to an intermediate connecting link 296 representing a portion of a guiding link 252 pivoted to the support at 254. Furthermore, on each side of the chair, the upper end of a front connecting link 244 is pivoted to the seat at 248, and the lower end of said front connecting link 244 is pivoted to said intermediate connecting link 296 at 241. Thus, the pivotally interconnected downward extension 238 of the back-rest, the link-chain composed of the lower connecting link 240, of the intermediate connecting link 296 and of the front connecting link 244, and the seat 232 form a polygonal link-system in the shape of a quinquelateral link-system which is swingably mounted on the support 220 at the pivotal connection 236 between the back-rest and the seat. The movements of said quinquelateral link-system are controlled by said guiding link 252 pivoted to the support at 254 and including the intermediate connecting link 296 of the link-chain as mentioned above. It is to be understood, that, if desired, the guiding link and the intermediate connecting link could be made of two separate members which are rigidly connected with each other by screws or the like.

On each side of the chair, one end of a controlling link 260 is pivoted at 262 to a leg-rest 256 pivoted to the seat 232 at 258. The other end of each controlling link 260 is pivoted at 265 to an element 298, which may be considered an extension of the guiding link 252 projecting outside the quinquelateral link-system. According to Fig. 5 the extension 298 is integral with the guiding link 252 a portion of which represents the intermediate connecting link 296, but of course the extension 298 and the guiding link 252 could be made of two separate members rigidly connected with each other by screws or the like. Furthermore, the extension 298 must not necessarily be in alignment with the guiding link 252 as shown in Fig. 5, if desired, the extension 298 could be attached to an intermediate point of the guiding link and could project sidewise therefrom.

As will be readily understood from the statements above, the guiding link 252 controls the movements of the members of the quinquelat-

eral link-system and the movements of the leg-rest. When the back-rest is swung about the pivot 236, the members of the chair shown in full line in the sitting position may be brought into a reclined position, for example into the extreme reclined position shown in dash and dot lines.

The sitting position is limited by a stop 268 and the extreme reclined position is limited by a stop 270. Both stops are mounted on the support 220 for abutting cooperation with the extension 238 of the back-rest or the back-rest 234 respectively.

Fig. 6 illustrates an arm-chair, wherein 320 generally indicates the support comprising side frames 322 and 324 connected with each other by transverse bars 327 and 329. The side frames include the arm-rests 330. The seat 332 is pivoted to the back-rest 334 at 336. The pivotally interconnected downward extension 338 of the back-rest 334, the link-chain composed of the lower connecting link 340 and of the front connecting link 344 and the seat 332 form a quadrilateral link-system swingably mounted on the support 320 at 336. The movements of said quadrilateral link-system are controlled by the guiding link 352, the upper end of which is pivoted to a member 321 of the support 320 at 354 and the lower portion of which is pivoted to the lower connecting link 340 at 343. Said guiding link 352 has an extension 398 projecting outside the quadrilateral link-system. One end of the controlling link 360 is pivoted to said extension 398 of the guiding link at 365, the other end of said controlling link 360 is pivoted at 362 to the leg rest 356 pivoted to the front portion of the seat 332 at 358.

If the movable members of the chair are pivotally connected with each other as described above, and if, for example, the back-rest 334 is swung backwards, the movable members of the chair may be brought from the sitting position shown in full lines into a reclined position, for example the extreme reclined position shown in dash and dot lines. In said extreme reclined position, limited by a stop 370 mounted on the support for cooperation with the seat, the back-rest, the seat and the leg-rest are in the positions indicated by 334', 332', 356'.

The movable members of the chair may be held in any desired position by means of a locking device generally indicated by 372 of a construction shown in Fig. 3.

The extension 338 of the back-rest, the lower connecting link 340, the front connecting link 344, the guiding link 352 and its extension 398 as well as the controlling link 360 are provided with series of holes 300, so that the pivots or pins 342, 343, 346, 354, 365 may be inserted into various selected holes for a change in the effective length of the various members of the chair resulting in a change in the angular movements of the various members of the chair.

Furthermore, if for example the movable members of the chair are held in the extreme reclined position by means of the locking device 372, the pivot 365 may be disengaged from the extension 398 of the guiding link and the controlling link 360, whereupon the leg-rest 356 may be swung by hand into the position 356'' in alignment with the seat being in the position 332'. When the leg-rest is in said position 356'', the hole at the right-hand end of the series of holes of the controlling link 360 is in register with a hole of the support, so that the pin 365'' may be

inserted into said registering holes, whereby the leg-rest is held in said position 356''.

As shown in Fig. 6, a stop 367 mounted on the seat 332 projects from the front end of the latter for cooperation with the leg-rest 356; when the leg-rest is in the position 356'' in line with the seat being in the reclined position 332', the leg-rest abuts against said stop then being in the position 367'. Said stop 367 prevents an accidental overturning of the leg-rest over its alignment with the seat when the seat is under the load of an occupant, the locking device 372 is loosened, and the pin 365'' is not yet removed from the hole of the support.

Moreover, if the members of the chair are in the full-line sitting position and if after a loosening of the locking device 372 either the pin 342 or the pin 346 is removed, the seat 332 will drop into a horizontal position 332''' limited by a stop 392 mounted on the member 321 of the support 320. Now, the back-rest 334 may be freely swung into the horizontal position 334''' limited by the transverse member 327 and in line with the horizontal position of the seat. After disengaging the pin 365 from the extension 398 of the guiding link and the controlling link 360 the leg-rest may be freely swung into the horizontal position 356''' in alignment with the horizontal position of the seat. When the leg-rest is in said position 356''', the hole at the left-hand end of the series of holes of the controlling link 360 is in register with a hole of the support, so that the pin 365''' may be inserted into said registering holes, whereby the leg-rest is held in said horizontal position 356'''. Thus, the arm-chair shown in Fig. 6 may be readily converted into a bed-like article of furniture.

If desired, the controlling link 360 may also be made in the shape of a telescopic element having two members slidably and adjustably connected with each other for an adjustment of the length of the controlling link.

Fig. 7 illustrates an arm-chair, wherein the controlling mechanism operates substantially according to the same principle as the controlling mechanism shown in Fig. 6. According to Fig. 7, however, the quadrilateral link-system 438, 440, 444, 432 is pivoted to the support 420 at 437, and said pivotal connection 437 does not coincide with the pivotal connection 436 between the seat 432 and the back-rest 434. Furthermore, according to Fig. 7, the extension 428, the lower connecting link 440, the front connecting link 444, the guiding link 452 and the controlling link 460 are arranged in the center of the chair, while according to Fig. 6, said elements are arranged on each side of the chair. The leg-rest 453 is pivoted to the seat 432 at 458. Instead of the connection between the leg-rest and the seat shown in Fig. 7, the leg-rest 456 may be connected with the seat 432 in the manner, shown in Fig. 9. According to Fig. 9, the frame of the seat 432 is provided with a slot 433 receiving the element 435 pivoted to the frame of the seat at 459 and secured to the leg-rest 456 by screws 461. The construction shown in Fig. 9 permits the arrangement of the pivot 459 at the highest point possible and eliminates an interfering of the element 435 with a cover to be placed around the frame of the seat 432.

Fig. 8 diagrammatically illustrates a controlling mechanism which is somewhat similar to the mechanism shown in Fig. 7, wherein, however, the pivotal connection between the guiding link and the support is in a plane above the seat

532. Therefore, the mechanism shown in Fig. 8 requires the arrangement of a guiding link 552 on each side of the chair. Said two guiding links 552 and their extensions 598 are connected with each other by transverse rods 543 and 565. The transverse rod 543 is rotatable in a hole of a single lower connecting link 540 arranged in the center of the chair. One end of said lower connecting link 540 is pivoted at 542 to the extension 538 of the back-rest 534, and the other end of said lower connecting link is pivoted at 546 to one end of the front connecting link 544, the other end of which is swingable on a transverse rod 548 of the seat 532. One end of a single controlling link 560 is swingably mounted on the transverse rod 565, while the other end of said controlling link 560 is swingably mounted on a transverse rod 562 of the leg-rest 556.

In the embodiment of a chair shown in Fig. 10, 632 indicates the seat pivoted to the back-rest 634 at 636. Similar to the embodiment shown in Fig. 5, the pivotally interconnected extension 638 of the back-rest, the lower connecting link 640, the intermediate connecting link 696, the front connecting link 644 and the seat 632 form a quinquelateral link-system swingably mounted on the support 620 at 636. On each side of the chair, the upper end of each guiding link 652 is pivoted to the support at the point 654 above the level of the seat. The lower portion of each guiding link 652 is rigidly connected with the intermediate connecting link 696. According to said Fig. 10, on each side of the chair each controlling link 660 is pivoted to an intermediate point of the guiding link 652 at 664. The other end of each controlling link 660 is pivoted at 662 to the leg-rest 656 pivoted to the seat at 658. Again, the guiding links 652 control the movements of the members of the quinquelateral link-system and of the leg-rest. The sitting position of the members of the chair shown in full lines is limited by the stop 668 mounted on the support and the extreme reclined position of the members of the chair shown in dash and dot lines is limited by the stop 670 mounted on the support.

The adjustable reclining chair shown in Fig. 11 is similar to the chair shown in Fig. 10, with the exception, however, that the seat 732 is not pivotally connected with the back-rest 734. According to Fig. 11, the back-rest 734 having a downward extension 738 is pivoted to the support 720 at 736, and the seat 732 is pivoted to the support at 704. The pivots 736 and 704 are arranged at a small distance from each other. Thus, the pivotally interconnected movable extension 738 of the back-rest, the movable lower connecting link 740, the movable intermediate connecting link 796, the movable front connecting link 744, the movable seat 732, and the stationary portion of the support 720 between the pivots 704 and 736 from the members of a hexagonal link-system. The guiding link 752 pivoted to the support 720 at 754 and rigidly connected with intermediate connecting link 796 serves to control the movements of the movable members of said hexagonal link-system. Furthermore, said guiding link 752 controls the movements of the leg-rest 756 pivoted to the seat 732 at 758 through the medium of the controlling link 760, the ends of which are pivotally connected with said leg-rest and an intermediate point of said guiding link.

According to the embodiment of a chair shown in Fig. 12, the back-rest 834 is pivoted to the

support 820 at 836 at a point spaced from the pivotal connection 804 between the rear end of the seat 832 and the support. Adjacent ends of the lower connecting link 840 and the front connecting link 844 are pivotally connected with each other at 846. The rear end of the lower connecting link 840 is pivoted to the downward extension 838 of the back-rest 834 at 842, and the upper end of the front connecting link 844 is pivoted to the seat 832 at 848. Thus, the pivotally interconnected movable extension 838 of the back-rest, the movable lower connecting link 840, the movable front connecting link 844, the movable seat 832, and the stationary portion of the support 820 between the pivots 804 and 836 form the members of a quinquelateral link-system. The guiding link 852 pivoted to the support 820 at 854 and pivoted to the lower connecting link 840 at 843 controls the movements of the movable members of said quinquelateral link-system. The extension 898 of the guiding link is pivoted to said guiding link at 843 and, thus, is swingable relative to the main body 852 of said guiding link. As shown in Figs. 12 and 13, the main body of said guiding link is provided with a cam-like lug 806 arranged for engagement with said swingable extension 898, so that the latter may be held in alignment with the main body 852 of the guiding link during a swinging movement of said main body about the pivot 854. One end of the controlling link 860 is pivoted to the extension 898 of the guiding link at 865, the other end of said controlling link is pivoted at 862 to the leg-rest 856 swingably mounted on the seat 832 at 858. When the members of the chair are in the position shown in full lines in Fig. 12, the back-rest, seat, and leg-rest may be brought into a reclined position, for example the extreme reclined position 834', 832', 856' shown in dash and dot lines, by swinging the back-rest about its pivot.

The movable members of the chair may be held in any desired position by means of a locking device 872 of the type shown in Figs. 1 and 3.

As mentioned above, the extension 898 of the guiding link is swingable about the pivot 843. Furthermore, said extension 898 is provided with a lug 806 as shown in Figs. 12 and 13. If the back-rest and seat are held in a predetermined position, for example the sitting position shown in full lines in Fig. 12, by means of the locking device 872, the leg-rest 856 may be swung by hand about its pivot 858 into the position 856'', wherein, the swingable extension 898 being in the position 898'' is in alignment with the controlling link being in the position 860''. Now, when a slight pressure is exerted on the leg-rest, for example by the legs of the occupant resting in the chair, the extension 898 and the controlling link 860 are moved slightly beyond said straight line, until the lug 806 of the extension abuts against the controlling link, whereby said elements are locked and held in a predetermined position relative to each other. Now, the extension 898 acts as a part of the controlling link 860, which now may be considered as being pivoted to the guiding link 852 at 843. Thus, upon loosening the locking device 872, the back-rest, seat, and leg-rest may be brought from the position 834, 832, 856' into a reclined position by swinging the back-rest about its pivot 836; under such circumstances, the extreme reclined position is obtained, when the leg-rest is in alignment with the seat.

According to Figs. 12 and 13, the pivot between the extension 898 of the guiding link and the guiding link 852 coincides with the pivot between the guiding link and the lower connecting link 840. If desired, however, the extension of the guiding link may be pivoted to the guiding link at a point spaced from the pivotal connection of the guiding link with a connecting link of the polygonal link-system.

Furthermore, as shown in Fig. 14, the controlling element 998 swingably mounted at 999 on the guiding link 952 must not necessarily be in the shape of an extension of the guiding link projecting outside the polygonal link-system. According to said Fig. 14, the controlling element 998 is arranged within the polygonal link-system which may be of the type shown in any of the above-described Figs. 1, 4-8, or 10-12. One end of the controlling element 998 is pivoted to the guiding link 952 at 999, the upper end of which is pivoted to the support (not shown) at 954 and the lower end of which is pivoted at 943 to the lower connecting link 940. The other end of the controlling element 998 is pivoted to one end of the controlling link 960 at 965, the other end of which is pivoted at 962 to the leg-rest 956 swingably mounted on the seat 932. The lug 906 secured to the guiding link 952 is arranged for engagement with the controlling element 998 so as to hold the latter in alignment with the guiding link during a movement thereof about its pivot 954. The lug 908 secured to the controlling element 998 forms an abutment for the controlling link 960 when the controlling element is swung about its pivot 999 and is brought into alignment with the controlling link.

The chairs shown in Figs. 4, 5, 7, 10 and 11 are not equipped with a locking device but it is understood, that a locking device as shown in Figs. 1 and 3 or any other suitable locking device may be arranged on said chairs for holding the movable members of the chair in any desired position.

I have described preferred embodiments of my invention, but it is understood that this disclosure is for the purpose of illustration, that the invention may also be applied to various other types of articles of furniture such as garden chairs, chairs for use in railroad cars, chairs for use in airplanes, sofas, lounges, etc., and that various omissions or changes in shape, proportion and arrangement of parts, as well as the substitution of equivalent elements for those, herein shown and described, may be made without departing from the spirit and scope of the invention as set forth in the appended claims.

What I claim is:

1. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding link and a chain of connecting links including a lower connecting link at one end of the chain and a front connecting link at the other end of the chain, at least one of said connecting links being arranged below the plane of the seat-member, the upper end portion of said guiding link being pivoted to said support, the lower end portion of said guiding link being connected with at least one of said connecting links, said lower connecting link being pivoted to the downward extension of the back-rest-member, said front

connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to the structure of said guiding link, the other end portion of said controlling link being pivoted to the structure of said leg-rest.

2. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding link and a chain of connecting links including a lower connecting link at one end of the chain and a front connecting link at the other end of the chain, at least one of said connecting links being arranged below the plane of the seat-member, the upper end portion of said guiding link being pivoted to said support, the lower end portion of said guiding link being connected with at least one of said connecting links, said lower connecting link being pivoted to the downward extension of the back-rest member, said front connecting link being pivoted to the front portion of said seat-member, means pivotally connecting at least one of said back-rest and seat-members with said support, a leg-rest swingably mounted on the front portion of said seat-member, the structure of said guiding link including an extension, permanently rigid therewith, said extension of the guiding link structure projecting downwardly beyond the connection between the guiding link and the connecting link, and a controlling link, one end portion of said controlling link being pivoted to said downward extension of the guiding link structure, the other end portion of said controlling link being pivoted to the structure of said leg-rest.

3. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding link and a chain of connecting links including a lower connecting link at one end of the chain and a front connecting link at the other end of the chain, at least one of said connecting links being arranged below the plane of the seat-member, the upper end portion of said guiding link being pivoted to said support, the lower end portion of said guiding link being connected with at least one of said connecting links, said lower connecting link being pivoted to the downward extension of the back-rest-member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to an intermediate point of said guiding link between its connections with the connecting link and the support, the other end portion of said controlling link being pivoted to the structure of said leg-rest.

4. An article of repose for supporting the body of a person, comprising in combination: a support, a constrained linkage having stationary

link-means and a plurality of movable links, said stationary link-means being included in said support, said movable links including a seat-member, a downward extension of a back-rest member, a guiding link and a chain of connecting links including a lower connecting link at one end of the chain and a front connecting link at the other end of the chain, at least one of said connecting links being arranged below the plane of the seat member, one end portion of said guiding link being pivoted to said support, the other end portion of said guiding link being connected with at least one of said connecting links, said lower connecting link being pivoted to the downward extension of the back-rest-member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to the structure of said guiding link, the other end portion of said controlling link being pivoted to the structure of said leg-rest.

5. An article of repose for supporting the body of a person, comprising in combination: a support, a constrained linkage having stationary link-means and a plurality of movable links, said stationary link-means being included in said support, said movable links including a seat-member, a downward extension of a back-rest member, a guiding link and a chain of connecting links including a lower connecting link at one end of the chain and a front connecting link at the other end of the chain, at least one of said connecting links being arranged below the plane of the seat member, one end portion of said guiding link being pivoted to said support, the other end portion of said guiding link being connected with at least one of said connecting links, said lower connecting link being pivoted to the downward extension of the back-rest member, said front connecting link being pivoted to the front portion of said seat-member, means pivotally connecting at least one of said back-rest and seat-members with said support, a leg-rest swingably mounted on the front portion of said seat-member, the structure of said guiding link including an extension, permanently rigid therewith, said extension of the guiding link structure projecting downwardly beyond the connection between the guiding link and the connecting link, and a controlling link, one

end portion of said controlling link being pivoted to said downward extension of the guiding link structure, the other end portion of said controlling link being pivoted to the structure of said leg-rest.

6. An article of repose for supporting the body of a person, comprising in combination: a support, a constrained linkage having stationary link-means and a plurality of movable links, said stationary link-means being included in said support, said movable links including a seat-member, a downward extension of a back-rest-member, a guiding link and a chain of connecting links including a lower connecting link at one end of the chain and a front connecting link at the other end of the chain, at least one of said connecting links being arranged below the plane of the seat-member, one end portion of said guiding link being pivoted to said support, the other end portion of said guiding link being connected with at least one of said connecting links, said lower connecting link being pivoted to the downward extension of the back-rest-member, said front connecting link being pivoted to the front portion of said seat-member, means pivotally connecting at least one of said back-rest and seat-members with said support, a leg-rest swingably mounted on the front portion of said seat-member, and a controlling link, one end portion of said controlling link being pivoted to an intermediate point of said guiding link between its connections with the connecting link and the support, the other end portion of said controlling link being pivoted to the structure of said leg-rest.

ANTON LORENZ.
